LATCHING DEVICE

Henry J. McDermott, Collingdale, Pa., assignor
to American Viscose Corporation, Wilmington,
Del., a corporation of Delaware

Application November 13, 1945, Serial No. 628,213

11 Claims. (Cl. 287—53)

1

This invention relates to devices for fastening various parts, such as spools, sleeves, discs, hubs, or the like, to a rod or shaft, either at the end thereof or at spaced intervals along the length thereof.

The principal object of the invention is to provide a latching device of the simplest possible construction requiring the fewest parts and the minimum amount of special machining of the portions of the rod or shaft adapted to receive the device. A further and important object of the invention is to provide a device of this type which is so constructed that all parts remain permanently in place on the rod or shaft, arbor or the like prior to, during and after the placing or removal of the parts which are to be retained by the fastening devices upon the rod or the like. This assures that no parts may become lost as a result of the mounting or removal of such parts upon the rod or the like. Other objects and advantages of the invention will be apparent from the drawing and the description thereof hereinafter.

In the drawing, which is illustrative of preferred embodiments of the invention,

Figure 1 is a sectional elevation of one form of the device,

Figure 2 is a corresponding unsectioned elevation,

Figure 3 is a transverse section taken on the line III—III of Figure 1,

Figure 4 is a transverse section taken on line IV—IV of Figure 1,

Figure 5 is a sectional elevation of a modification,

Figure 6 is a transverse section taken on line VI—VI of Figure 5,

Figure 7 is a transverse section through a rod provided at an intermediate position with a modified form of the invention,

Figure 8 is a transverse cross section on line VIII—VIII of Figure 7,

Figure 9 is a sectional elevation of another modification, and

Figure 10 is a plan view of the latching device of Figure 9 with the cap removed.

As shown in Figures 1 to 4, the fastening device of the invention is shown in place on the end of a hollow standard in the form of a rod or tube 2 carrying a supporting plate 3 for a cake 4 of rayon or the like in unwinding position. For this purpose, a conventional Celluloid cuff 5 is placed on the internal periphery of the cake 4 and the knitted fabric sleeve wrapper 6 is folded back upon itself upon the top and laid over the

2

platform 3 to expose the exterior periphery of the cake so that the strand 7 may be unwound from the outer convolutions thereof. An inverted "pie-plate" 8 is laid upon the cake and has a sleeve or hub 9 secured thereto. The hub 9 serves conveniently as a handle. The plate 8 rests upon the Celluloid or paper cuff 5 and to prevent the pie-plate from being lifted from the standard in case of snagging or tangling of the strand 7, the device of the present invention is inserted into the open end of the standard in which it is retained by a transverse pin 11.

As shown in this embodiment of the invention, the device comprises a bifurcated member A set in and partially extending out of a recess or bore of the standard 2. Each prong consists of a resilient member which is adapted to be sprung inwardly though it normally takes the position shown in Figure 1. Each resilient member has a latching element 12 projecting outwardly from an intermediate portion of its length so as to project beyond the circumference of the standard 2 and thereby retain the sleeve 9 in place. The latching face of the element 12 has a portion 13 which engages the sleeve 9 inclined substantially perpendicularly to the axis of the standard. The other face 14 of the latching element slopes inwardly to the body of the resilient member. As shown, the puncture of the body of the member to this sloped surface 14 may be somewhat necked down and a cap 15 having its peripheral wall 16 in the form of a sleeve is adapted to surround the portion of the resilient member projecting beyond the neck. The cap 15 has an inwardly turned bead 17 which normally encircles the neck formed about the two resilient members. The end wall of the cap is sufficiently spaced from the bead 17 to permit the sleeve to slide axially of the resilient members a sufficient distance to pinch them together enough to allow the sleeve 9 to pass from the latching element 12. Preferably, when the prongs are pinched to their maximum extent, the latching faces 13 overlap the edges of the recess or bore in the rod 2 and limit the movement of the member A into the recess or bore thereof.

When first applying the pie-plate over a standard or equivalent shaft provided with the latching device of the present invention, it is merely necessary to slip the pie-plate over the cap 15 and to force it downwardly over the latching elements 12 which are thereby pinched together, until the sleeve 9 of the pie-plate passes beyond the latching elements, at which time they spring outwardly and prevent accidental removal of the

pie-plate. In removing the pie-plate from the standard, it is merely necessary for an operator to place his thumb against the end of the cap 15 and two or more fingers of the same hand about the sleeve 9 so that at least one finger engages each of the opposite sides thereof, pressing down with the thumb while pulling upwardly on the sleeve 9 with the fingers. When the latching elements 12 are sufficiently retracted by the bead 17 of the cap, the sleeve 9 will slide over them and continued pulling movement by the fingers draws it entirely over the end of the standard.

Figures 5 and 6 show a modification in which the cross section of the bifurcated member is altered to enhance the springiness. Such alteration merely consists in giving the inner surface of each resilient member or prong a concave curvature. A further modification is to provide only one of such resilient members with a latching element 12.

Figures 7 and 8 show a modification in which a solid shaft 21 is provided with one or more fastening elements positioned intermediate of its length. This shaft may be used to support a plurality of objects, such as wound rayon cakes, so that they are spaced apart thereon. Only one fastening element is shown and it comprises a resilient member 22 having the latch element 23 extending outwardly from an intermediate portion of its length. One end of the member 22 may be bent back upon itself as shown at 24. The member 22 is positioned in a recess 25 taking almost but not quite a quadrantal shape as shown in the cross section of Figure 8. The portion of the rod in the vicinity of the device has a reduced diameter so that it accommodates a sleeve 26 slidably thereon, the sleeve 26 having an external diameter substantially the same as the diameter of the shaft. As shown, the sleeve 26 normally overhangs somewhat the body of the member 22 adjacent the sloped surface of the latching element 23 thereon. An abutment or pin 27 extending into the other end of the recess may cooperate with the overhanging portion of the sleeve to retain the resilient member within the recess. If desired, however, the resilient member may be fastened to the recess along the reversely bent portion 24. Although two such resilient members may be provided in recesses at a given position of the rod, a single one may be used instead, particularly when it is desirable to weaken the shaft to the minimum extent.

In a manner analogous to that of the embodiment shown in Figures 1 to 6, the resilient member or members 22 of this embodiment normally takes the position shown in the drawing but are moved into retracted position entirely within the sleeve 26 when that sleeve is slid axially of the rod.

Figures 9 and 10 show a modification of the form of latch shown in Figures 1 to 4 in which the bifurcated member A has a flattened cross-section (see Figure 10 especially) and the bead end of each prong has a laterally overhanging projection 30, the projection of one prong extending in a direction opposite to that of the projection on the other prong. This arrangement allows the cap 15 to be applied or removed at will merely by pinching the prongs together while shifting them laterally (by pressing together in the direction of the arrows in Fig. 10) until the bead 17 passes over the heads of the prongs. While the cap 15 is in place, the projections 30 engage the bead 17 to prevent the

cap from being removed accidentally during use. Another variation is the provision of the sloped face 14a extending inwardly from the portion 13 of the latching face. This additional slope reduces the effort needed to contract the prongs when removing or applying the plate 8 since the member A moves downwardly in the recess in rod 2 when the thumb of the operator presses cap 15 downwardly.

While the invention has been illustrated with particular reference to the holding of spools or other wound packages of yarns and the like, it is to be understood that the device of the invention may serve to retain releasably any parts, devices, or the like which may be positioned upon a rod or shaft. Again, whereas the invention has been illustrated with particular reference to retaining parts upon rods or the like having a circular periphery, it is to be understood that rods or shafts having peripheries of rectangular, square, hexagonal, elliptical or any other shape may be utilized.

It is to be understood that changes and variations may be made without departing from the spirit and scope of the invention as defined in the appended claims.

I claim:

1. In a device for releasably retaining a part on a rod extending therethrough and having a recess, a radially inwardly retractable resilient member secured in the recess in the rod and extending generally longitudinally with respect thereto, a latching element projecting laterally outwardly from the member at a position intermediate of its length and having in its normal position of rest, an outer limit of projection which is spaced beyond the outer diameter of the rod a distance no greater than the distance that the member is inwardly retractable, one face of the element being gradually sloped inwardly and the other face of the element having a portion inclined abruptly to the body of the member and a sleeve normally mounted co-axially with respect to the rod with a portion surrounding that portion of the body of the member adjacent the gradually sloped surface of the latching element, said sleeve being movable axially with respect to the member and over the gradually sloped face thereof whereby it engages the element and retracts it inwardly.

2. In a device for releasably retaining a part on a rod extending therethrough and having a recess, a radially inwardly retractable resilient member secured in the recess in the rod and extending generally longitudinally with respect thereto, a latching element projecting laterally outwardly from the member at a position intermediate of its length and having in its normal position of rest, an outer limit of projection which is spaced beyond the outer diameter of the rod a distance no greater than the distance that the member is inwardly retractable, one face of the element being gradually sloped inwardly and the other face of the element having a portion inclined abruptly to the body of the member and a sleeve having an outside diameter at least as small as the diameter of the rod normally mounted co-axially with respect to the rod with a portion surrounding that portion of the body of the member adjacent the gradually sloped surface of the latching element, said sleeve being movable axially with respect to the member and over the gradually sloped face thereof whereby it engages the element and retracts it inwardly.

3. A device for releasably retaining a part on a rod extending therethrough comprising a retractable resilient member secured to one end of the rod and extending generally longitudinally with respect thereto, a latching element projecting laterally outwardly from the member at a position intermediate its length and having in its normal position of rest, an outer limit of projection which is spaced beyond the outer diameter of the rod a distance no greater than the distance that the member is inwardly retractable, one face of the element being gradually sloped inwardly and the other face of the element having a portion inclined substantially perpendicularly to the body of the member, and a sleeve normally mounted co-axially with respect to the rod with a portion surrounding that portion of the body of the member adjacent the gradually sloped surface of the latching element, said sleeve being movable axially with respect to the member and over the gradually sloped face thereof whereby it engages the element and retracts it inwardly.

4. A device for releasably retaining a part on a rod extending therethrough comprising a retractable resilient member secured to one end of the rod and extending generally longitudinally with respect thereto, a latching element projecting laterally outwardly from the member at a position intermediate its length and having in its normal position of rest, an outer limit of projection which is spaced beyond the outer diameter of the rod a distance no greater than the distance that the member is inwardly retractable, one face of the element being gradually sloped inwardly and the other face of the element having a portion inclined substantially perpendicularly to the body of the member, and a sleeve having an outside diameter at least as small as the diameter of the rod normally mounted co-axially with respect to the rod with a portion surrounding that portion of the body of the member adjacent the gradually sloped surface of the latching element, said sleeve being movable axially with respect to the member and over the gradually sloped face thereof whereby it engages the element and retracts it inwardly.

5. A device for releasably retaining a part on a rod extending therethrough comprising two retractable resilient members secured to one end of the rod and projecting generally axially therefrom, a latching element projecting laterally outwardly from at least one of the members at a position intermediate of its length and having in its normal position of rest, an outer limit of projection which is spaced beyond the outer diameter of the rod a distance no greater than the distance that the member is inwardly retractable, one face of the element being gradually sloped inwardly and the other face of the element having a portion abruptly inclined to the body of the member, and a cap mounted about the outermost projecting portion of the resilient members, said cap being movable axially with respect to the members and over the gradually sloped faces thereof whereby each element is engaged thereby and retracted inwardly.

6. A device for releasably retaining a part on a rod extending therethrough comprising two retractable resilient members secured to one end of the rod and projecting generally axially therefrom, a latching element projecting laterally outwardly from at least one of the members at a position intermediate of its length and having in its normal position of rest, an outer limit of pro-

jection which is spaced beyond the outer diameter of the rod a distance no greater than the distance that the member is inwardly retractable, one face of the element being gradually sloped inwardly and the other face of the element having a portion abruptly inclined to the body of the member, and a cap having an outside diameter at least as small as the diameter of the rod mounted about the outermost projecting portion of the resilient members, said cap being movable axially with respect to the members and over the gradually sloped faces thereof whereby each element is engaged thereby and retracted inwardly.

7. A device for releasably retaining a part on a rod extending therethrough comprising a bifurcated unit having two retractable resilient members, said unit being secured to one end of the rod and with its members extending axially therefrom, each member having a latching element projecting laterally outwardly therefrom at a position intermediate of its length and having in its normal position of rest, an outer limit of projection which is spaced beyond the outer diameter of the rod a distance no greater than the distance that the member is inwardly retractable, one face of the element being gradually sloped inwardly and the other face of the element having a portion inclined abruptly to the body of the member, and a sleeve mounted about the outer projecting portions of the members, said sleeve being movable axially with respect to the members and over the gradually sloped faces thereof whereby it engages the elements and retracts them inwardly.

8. A device for releasably retaining a part on a rod extending therethrough comprising a bifurcated unit having two retractable resilient members, said unit being secured to one end of the rod and with its members extending axially therefrom, each member having a latching element projecting laterally outwardly therefrom at a position intermediate of its length and having in its normal position of rest, an outer limit of projection which is spaced beyond the outer diameter of the rod a distance no greater than the distance that the member is inwardly retractable, one face of the element being gradually sloped inwardly and the other face of the element having a portion inclined abruptly to the body of the member, and a sleeve having an outside diameter at least as small as the diameter of the rod mounted about the other projecting portions of the members, said sleeve being movable axially with respect to the members and over the gradually sloped faces thereof whereby it engages the elements and retracts them inwardly.

9. A device for releasably retaining a part on a rod extending therethrough comprising a reduced diameter portion of the rod, said rod having a recess extending longitudinally along a portion of the reduced diameter portion of the rod, a retractable resilient member secured in the recess, a latching element projecting laterally outwardly from the member at a position intermediate of its length and having in its normal position of rest, an outer limit of projection which is spaced beyond the outer diameter of the rod a distance no greater than the distance that the member is inwardly retractable, one face of the element being gradually sloped inwardly and the other face of the element having a portion inclined abruptly to the body of the member, a sleeve positioned on the reduced diameter portion

of the rod, said sleeve normally overlapping that portion of the body of the member adjacent the gradually sloped surface of the latching element, said sleeve being movable axially along the reduced diameter portion of the rod and over the gradually sloped face of the latching element whereby it engages the element and retracts it inwardly.

10. A device for releasably retaining a part on a rod extending therethrough comprising a reduced diameter portion of the rod, said rod having a recess extending longitudinally along a portion of the reduced diameter portion of the rod, a retractable resilient member secured in the recess, a latching element projecting laterally outwardly from the member at a position intermediate of its length and having in its normal position of rest, an outer limit of projection which is spaced beyond the outer diameter of the rod a distance no greater than the distance that the member is inwardly retractable, one face of the element being gradually sloped inwardly and the other face of the element having a portion inclined abruptly to the body of the member, a sleeve positioned on the reduced diameter portion of the rod and having an outside diameter at least as small as the diameter of the rod, said sleeve normally overlapping that portion of the body of the member adjacent the gradually sloped surface of the latching element, said sleeve being movable axially along the reduced diameter portion of the rod and over the gradually sloped face of the latching element whereby it engages the element and retracts it inwardly.

11. In a device for releasably retaining a part

5 on a rod extending therethrough and having a recess, a radially inwardly retractable resilient member secured in the recess in the rod and extending generally longitudinally with respect thereto, a latching element projecting laterally outwardly from the member at a position intermediate of its length and having in its normal position of rest, an outer limit of projection which is spaced beyond the outer diameter of the rod a distance no greater than the distance that the member is inwardly retractable, one face of the element being gradually sloped inwardly and the other face of the element having a portion inclined abruptly to the body of the member and 10 a second portion sloped inwardly from the first portion and a sleeve normally mounted co-axially with respect to the rod with a portion surrounding that portion of the body of the member adjacent the first-mentioned gradually sloped surface of the latching element, said sleeve being movable axially with respect to the member and over the gradually sloped face thereof whereby it engages the element and retracts it inwardly.
